UNITED STATES PATENT OFFICE.

ROBERT PRESTON MOODIE AND CHARLES WARREN BALL, OF OTTAWA, ONTARIO,
CANADA.

ELECTRIC IRON.

986,488.

Specification of Letters Patent. Patented Mar. 14, 1911.

Application filed August 14, 1908. Serial No. 448,623.

To all whom it may concern:

Be it known that we, ROBERT PRESTON MOODIE and CHARLES WARREN BALL, both of the city of Ottawa, in the county of Carleton, Province of Ontario, Canada, (post-office address is 417 Sparks street, Ottawa, Ontario,) having invented certain new and useful Improvements in Electric Irons, do hereby declare that the following is a full, clear, and exact description of the same.

The invention relates to improvements in electric irons, as described in the present specification and illustrated by the accompanying drawings, that form part of the same.

The invention consists essentially in the novel construction and arrangement of parts whereby the efficiency of the heating elements is increased, and the resistance heat of the electrical current is more directly applied to heat the iron, and whereby the iron when reversed can be used, in combination with a suitable stand, as a heater.

The objects of the invention are to provide a combined electric sad iron and heater, economical to manufacture, and for use, efficient in operation, and one that can be readily transported from place to place.

In the drawings:—Figure 1. is a perspective view of the iron in reversed position used as a heater. Fig. 2. is an elevation of the iron in upright position, used as an iron. Fig. 3. is a horizontal section through the iron showing the heating elements. Fig. 4. is a section on the line 2—2, of Fig. 3. Fig. 5. is a section along the line 3—3 of Fig. 3.

Like numerals of reference indicate corresponding parts in each figure.

Referring to the drawings, A represents the body of the iron of suitable material and shape, B, the handle thereof, and C the stand.

To prevent undue heating of the handle B, same is not connected directly to the body A, of the iron, but is provided with the plate 10, which extends in the recess 11 having the lining 12, of any suitable heat insulating material, said plate 10, being detained in position by the screw 13, or other suitable clamping means.

The body of the iron is formed on the interior with the longitudinally extending cylindrical recesses 14 and 15, opening at the back, and having therein the cylindrical

cores 16 and 17, of suitable insulating, heat resisting material, said cores being provided with the annular flanges 18 and 19, formed at opposite ends and adapted to support the intermediate parts of the cores out of contact with the sides of the recesses. Greater rigidity is given to the cores by means of the rods 20 and 21, extending therethrough, connected to a rear plate 22, of insulating material, and provided at their outer extremities with the suitable binding posts 23 and 24.

The binding posts and rear plate are protected by the movable casing D, extending along the top and sides at the back of the iron, and resting on the integral bottom flange, of the iron, 25, and secured in position by means of the nut 26, on the screw 27 secured to the body of the iron and extending through the said casing D.

The casing D is formed on top with the aperture 28, through which the cord 29 containing the conducting wires extends, said aperture being preferably provided with a flange 30, formed around the exterior thereof, about which is wound the spiral spring 31, extending up said cord and affording protection to same; the end 32, of the spiral spring being preferably brought down and clamped beneath the nut 26.

The electrical connections are effected in the usual way, the electrical wires 33 and 34 being wound on the cores, the current passing, first through the wire on one core, back through the rod of said core, through the rod of the opposite core and back through the resistance wire on the said opposite core.

The cylindrical recess 35 in the body of the iron is provided for the purpose of conveniently heating a curling tongs or the like, and is adapted to hold same.

From the foregoing it will be readily seen that, the heat of the resistance wire is directly communicated to the body of the iron itself, and that, while none of the heat produced can escape, the recesses being well toward the center of the iron, a very small amount of heat radiation will occur.

The rods 20 and 21, besides giving additional support to the cores 16 and 17, simplify the construction by enabling the binding posts 23 and 24 to be formed on the extremities thereof.

As changes may be made in the foregoing

construction, and many apparently widely different embodiments of our invention may be resorted to, without departing from the spirit or scope thereof, it is intended that 5 all matter contained in this specification and drawings, shall be interpreted as illustrative, and not in a limiting sense. It is also to be understood that the language of the accompanying claims is intended to 10 cover such generic and specific features of the invention as might be said to be included thereby.

What we claim for our invention is:—

1. An electric iron having cylindrical recesses therein, hollow cores of insulating material formed with flanges at each end, adapted to fit in said recesses, heating-conductors wound on said cores between said flanges out of contact with and in close 20 proximity to said iron, said heating-conductors being insulated from said iron by said end-flanges; rods extending through said hollow cores, binding posts formed on said rods, a rear-plate of insulating material connecting the cores with said rear-plate, a casing member inclosing the rear-plate, a bottom flange formed integral with the body of the iron adapted to support said casing member.
- 25 2. An electric iron having cylindrical re-

cesses therein, hollow cores of insulating material, formed with supporting collars at each end, returning wires through said cores, heating-conductors wound on said cores between said supporting collars out of contact 35 throughout their entire length with said iron by means of said supporting collars, binding posts formed on said returning wires, a rear-plate of insulating material connecting the cores with said rear-plate, a casing member inclosing the rear-plate, means for supporting same from the body of the iron whereby the connections are not affected by the heat of the elements.

3. An electric iron having cylindrical 45 holes therein, hollow cores of insulating material formed with end supporting collars, adapted to fit in said holes, heating-conductors arranged on said cores between said collars, so that said conductors lie throughout 50 their entire length in close proximity to the surrounding metal, whereby the heat energy generated is directly transmitted to said surrounding metal.

ROBERT PRESTON MOODIE.
CHARLES WARREN BALL.
